US00D963065S

(12) **United States Design Patent** (10) Patent No.: **US D963,065 S**
(45) Date of Patent: ** Sep. 6, 2022

(54) **TOY BUILDING ELEMENT**

(71) Applicant: **LEGO A/S**, Billund (DK)

(72) Inventor: **Paul Marion Wood**, Vejle (DK)

(73) Assignee: **LEGO A/S**, Billund (DK)

(**) Term: **15 Years**

(21) Appl. No.: **29/727,129**

(22) Filed: **Mar. 9, 2020**

(30) **Foreign Application Priority Data**

Jan. 21, 2020 (EM) 007537964-0013

(51) **LOC (13) Cl.** **21-01**

(52) **U.S. Cl.**

USPC **D21/500**

(58) **Field of Classification Search**

USPC D21/484, 485, 489, 490, 491, 493, 494,

(57) **CLAIM**

The ornamental design for a toy building element, as shown and described.

DESCRIPTION

FIG. 1 is a top perspective view of the toy building element; FIG. 2 is a bottom perspective view thereof; FIG. 3 is a top plan view thereof; FIG. 4 is a bottom plan view thereof; FIG. 5 is a left side elevational view thereof; FIG. 6 is a rear elevational view thereof; FIG. 7 is a front elevational view thereof; and, FIG. 8 is a right side elevational view thereof.

The broken lines in the drawings are for the purposes of illustrating portions of the article that form no part of the claimed design. The dash-dot broken lines represent the bounds of the claim which form no part of the claimed design.

1 Claim, 8 Drawing Sheets
